UNITED STATES PATENT OFFICE.

LEWIS K. DALRYMPLE, OF CHICAGO, ILLINOIS, ASSIGNOR OF FOUR ONE-HUNDREDTHS TO ALBERT H. ADAMS, OF OAK PARK, ILLINOIS, AND FOUR ONE-HUNDREDTHS TO JOHN L. JACKSON, OF RIVER FORREST, ILLINOIS.

WHEEL.

Application filed September 20, 1920, Serial No. 411,553. Renewed August 15, 1925.

To all whom it may concern:

Be it known that I, LEWIS K. DALRYMPLE, a citizen of the United States, and a resident of Chicago, in the county of Cook and State of Illinois, have invented certain new and useful Improvements in Wheels, of which the following is a specification, reference being had to the accompanying drawings.

10 My invention relates to metal wheels of the type provided with a demountable tire-carrying rim, and more particularly to such wheels in which the hub is connected with the rim by a disc or disc-like member as distinguished from a separate spoke and felly construction. It has for its object to provide improved means for securing the demountable or tire-carrying rim in place, constructed and arranged so that such rim 15 may be very easily and quickly mounted or demounted, while at the same time it will be securely held in place when in position on the wheel; also to provide a metal wheel 20 of the type described which will be of substantial construction although comparatively light in weight, and which will be comparatively inexpensive to manufacture. I accomplish my object as illustrated in the accompanying drawings and as hereinafter 25 described. What I regard as new is set forth in the claims.

In the drawings,—

Fig. 1 is a side view showing the inner face of my improved wheel, some parts being broken away and some parts being in section;

Fig. 2 is an enlarged detail, being substantially a vertical section taken on line 2—2 of Fig. 3;

Fig. 3 is a transverse vertical section taken on line 3—3 of Fig. 1;

Fig. 4 is an enlarged detail being a partial vertical section of the rim portion of the wheel showing one of the studs by which 45 the tire carrying rim is held in position;

Fig. 5 is an enlarged detail, being a partial horizontal section taken on line 5—5 of Fig. 3; and

Fig. 6 is a view similar to Fig. 5, but 50 showing the condition of the parts when unlocked for removing the tire carrying rim.

Referring to the drawings,

10 indicates the hub which may be of any approved type but preferably comprises

a fixed flange 11 at one end portion thereof and a plate 12 removably mounted at the opposite end thereof. The intermediate portion of the wheel comprises a thin metal disc 13 secured to the hub in any suitable way and preferably provided with an offset portion adjacent to its inner margin, forming an annular shoulder 14 which rests on the outer edge of the flange 11. In the construction illustrated the disc 13 is braced by means of a dished sheet metal disc 15 of smaller diameter, which at its outer margin is fixedly secured to the intermediate portion of the disc 13, and adjacent to its inner margin is provided with an annular shoulder 16 which rests on the outer edge of the plate 12. The discs 13 and 15 are firmly secured to the hub by means of ring plates 17, 18 which overlap the inner marginal portions of said discs and clamp them respectively against the flange 11 and plate 12, through the instrumentality of bolts 19 and spacing sleeves 20 mounted on said bolts between said ring plates, as shown in Fig. 3. Preferably the disc 13 is provided with a reinforcing ring 21 welded to it opposite the point where the discs 13 and 15 are secured together, said ring and the discs being firmly united by rivets 22, as shown. While the construction thus far described has been explained rather fully such construction is to be understood merely as being preferential since the invention herein-after claimed, which has to do only with the construction by which the usual tire-carrying rim is supported and secured so that it 90 can easily be mounted or demounted, may well be embodied in metal wheels in which the disc is secured to the hub in various other ways.

Coming now to a description of the salient characteristics of my present invention, the disc 13 is provided at its outer margin with a laterally-extending flexible rim flange 23 so constructed that its free margin is capable of being deflected outwardly, or in other words, of swinging in and out relatively to the axis of the wheel about the outer marginal portion of the disc 13. This rim flange is preferably formed by bending the outer edge of said disc laterally at approximately 100 a right angle with the body of the disc, and slitting said rim flange transversely at several points 24 so that it is made flexible and

capable of expansion by the application of force to its inner face. This rim flange is adapted to support and firmly grip a tire-carrying rim 25 of any suitable type provided with a shoulder 26 or equivalent means at one side thereof adapted to abut against the outer portion of the disc 13 at the base of the rim flange 23. The rim 25 is adapted to carry a pneumatic tire 27 of any suitable type having a valve stem 28 extending inward through a suitable opening through the rim, as is common practice. Preferably the tire carrying rim 25 is provided with a boss 29 on its inner concave surface opposite the opening through which the valve stem extends, which boss is adapted to project through a suitable opening in the rim flange, as shown in Fig. 2. As is also clearly shown in that figure, the rim flange 23 is provided with a collar 30 adapted to fit about the boss 29. The normal diameter of the rim flange 23 is slightly less than the internal diameter of the tire-carrying rim 25, so that said rim fits loosely on the rim flange before its expansion and can then be applied or removed in the usual way. When, however, the rim flange is expanded it grips the tire-carrying rim firmly and prevents its removal. The means for expanding said rim flange comprises an expansible ring plate composed of a pair of substantially semi-circular bars 31 and 32 which are secured to the rim flange 23 adjacent to and at opposite sides of the collar 30, in the construction shown such bars having their ends in contact with said collar. These bars underlie and fit against the inner face of the rim flange 23 and at their opposite or free ends, are provided with wedge-shaped blocks 33 and 34, respectively, which are secured preferably by welding, upon the free end portions of said bars. The blocks 33 and 34 are spaced a short distance apart and a right and left hand screw 35 is interposed between them, as shown in Fig. 6, said screw being supported by a suitable bearing in the disc 13 and a second bearing in an ear 36 carried by the rim flange 23, as is best shown in Fig. 3. The screw 35 carries oppositely disposed wedges 37 adapted to cooperate with the wedge blocks 33, 34 to force the free ends of the bars 31, 32 apart and thereby exert outward pressure upon and expand the rim flange 23. As shown in Figs. 3 and 6, one end of the screw 35 projects through the disc 13 and is squared so that it can conveniently be rotated from that side of the wheel.

From the foregoing description it will be seen that the expansion of the bars 31, 32 operates to deflect the rim flange 23 outwardly by rocking it about the outer marginal portion of the disc 13, so as to cause it to firmly grip the inner surface of the tire-carrying rim, but when the pressure of said bars is

relaxed, the resiliency of said rim flange immediately restores it to its normal position, thereby releasing the tire-carrying rim. As only a few turns of the screw 35 are necessary to expand or contract the bars 31, 32, obviously the tire-carrying rim may be very easily and quickly secured or released. 70

For the purpose of preventing lateral displacement of the bars 31, 32 with reference to the rim flange 23 when they are not expanded, and also as an additional means for preventing such displacement of the tire-carrying rim when it is clamped on the rim flange, I provide two studs 38 and 39 carried by the bars 31 and 32, respectively, 75 and extending from the outer faces of such bars. As is best shown in Fig. 4, said studs extend through suitable openings in the rim flange 23, and when the tire-carrying rim is secured on the wheel, into registering openings in said tire-carrying rim. These openings are elongated sufficiently to permit of the necessary circumferential movement of the bars 31, 32, as shown in Fig. 4, but their width is such that objectionable lateral 80 movement is prevented. When the bars 31 and 32 are released from stress by the withdrawal of the wedge members 37, the studs 38 and 39 are released from engagement with the rim 25, thereby permitting said rim to be demounted. In the construction shown, two of the studs only are employed, each of such studs being spaced one-hundred and twenty degrees from the boss 29 which engages the collar 30. By this construction, the rim 25 has a three-point connection to the rim flange, in addition to its being held in position by the gripping action of said rim flange. 85

I have found in practice that by the use of my construction I am enabled to mount or demount the tire-carrying rim in a very few seconds, as the whole operation requires a few turns only of the screw 35. Suitable means may be provided if desired for locking the screw 35 against rotation so as to prevent accidental loosening of the tire-carrying rim, although I do not consider that necessary. 95

So far as I am aware, I am the first in the art to provide a metal wheel with a flexible rim flange extending laterally from the outer marginal portion of a disc or equivalent device by which it is connected with the wheel hub, and capable of being deflected outwardly to grip a tire-carrying rim; or such a device in which the deflection of the rim flange is accomplished by an expanding member placed within said rim flange so as to be capable of applying outward pressure against its inner face. The generic claims hereinafter made are, therefore, not to be restricted to the specific construction shown and described, but are to be construed broadly enough to include 105 110 115 120 125 130

such variations or modifications as would occur to those skilled in the art.

What I claim as my invention and desire to secure by Letters Patent, is—

5 1. A wheel having a hub, an intermediate portion, a laterally-extending flexible rim flange carried by said intermediate portion and adapted to fit within an outer rim and to be deflected angularly relatively to said 10 intermediate portion into gripping engagement with said outer rim, and means for so deflecting said rim flange.

15 2. A wheel comprising a hub, an intermediate portion, a laterally-extending rim flange connected at its inner margin with said intermediate portion and adapted to fit within an outer rim and to be deflected angularly relatively to said intermediate portion into gripping engagement with said 20 outer rim, and means for so deflecting said rim flange.

25 3. A metal wheel comprising a hub, a disc connected therewith and having a laterally-extending flexible rim flange at its outer margin adapted to fit within a tire-carrying rim and to be deflected outwardly into gripping engagement therewith, and means for so deflecting said rim flange.

30 4. A metal wheel comprising a hub, a disc connected therewith and having a laterally-extending rim flange the free margin whereof is adapted to swing outward about the outer marginal portion of said disc and is normally adapted to fit within a tire-carrying 35 rim, and means for swinging said rim flange outward into gripping engagement with the inner surface of said tire-carrying rim.

40 5. A metal wheel comprising a hub, a disc connected therewith and having a laterally-extending flexible rim flange integral with the outer marginal portion thereof adapted to fit within a tire-carrying rim and to be deflected outwardly into gripping engagement therewith, and means for so deflecting said rim flange.

45 6. A metal wheel comprising a hub, a disc connected therewith and having its outer marginal portion bent over at an approximately right angle to form a laterally-extending flexible rim flange adapted to fit within a tire-carrying rim and to be deflected outwardly into gripping engagement therewith, and means for so deflecting said rim flange.

50 7. A metal wheel comprising a hub, a disc

connected therewith and having a laterally-extending flexible rim flange at its outer margin adapted to fit within a tire-carrying rim and to be deflected outwardly into gripping engagement therewith, an expansible member lying within said rim flange, and means for expanding said member to deflect said rim flange outwardly.

55 8. A metal wheel comprising a hub, a disc connected therewith and having a laterally-extending flexible rim flange integral with the outer marginal portion thereof adapted to fit within a tire-carrying rim and to be deflected outwardly into gripping engagement therewith, an expansible member lying within said rim flange, and means for expanding said member to deflect said rim flange outwardly.

60 9. A metal wheel comprising a hub, a disc connected therewith and having its outer marginal portion bent over at an approximately right angle to form a laterally-extending flexible rim flange adapted to fit within a tire-carrying rim and to be deflected outwardly into gripping engagement therewith, an expansible member lying within said rim flange, and means for expanding said member to deflect said rim flange outwardly.

65 10. A metal wheel comprising a hub, a disc connected therewith and having a laterally-extending flexible rim flange at its outer margin adapted to fit within a tire-carrying rim and to be deflected outwardly into gripping engagement therewith, an expansible member lying within said rim flange and intermediately connected therewith, and having free end portions capable of movement relatively to said rim flange, and means for expanding said member to deflect said rim flange outwardly.

70 11. A metal wheel comprising a hub, a disc connected therewith and having a laterally-extending flexible rim flange at its outer margin adapted to fit within a tire-carrying rim and to be deflected outwardly into gripping engagement therewith, an expansible member lying within said rim flange and intermediately connected therewith, and having free end portions capable of movement relatively to said rim flange, means for expanding said member to deflect said rim flange outwardly, and studs carried by said member and engaging said rim flange and said tire-carrying rim.
